SIPHON VALVE UNIT FOR REFRIGERATORS

Charles H. Walbert, Oklahoma City, Okla.

Application October 13, 1943, Serial No. 506,104

6 Claims. (Cl. 137—69)

This invention relates generally to the class of refrigerators and is directed particularly to a novel humidifying means and intermittent siphon drain for use in those refrigerators employing ice as the refrigerating medium.

It is well understood that in the operation of refrigerators in which food is kept it is desirable that the air within the refrigerating chamber be kept at a suitable humidity. This is not easily accomplished in mechanically refrigerated structures or even in those refrigerators employing ice, although in the latter form of refrigerator the ice water in running from the refrigerator to a drain does supply a certain degree of humidity.

A principal object of the present invention is to provide in an ice refrigerator, a drainage receiving pan which is disposed in the lower part of the refrigerator food chamber to receive drippings from the ice chamber, whereby a substantial area of water is kept exposed in the food chamber to supply the desired amount of humidity to the air therein.

Another object of the invention is to provide, in association with the drip receiving receptacle which is maintained in the food chamber, a novel valve unit which is so designed that it will function intermittently to drain off the water to a pre-described low level from the drip receptacle, when the level of the water therein reaches a predetermined high.

Still another object of the invention is to provide in a receptacle and drainage valve unit as above described, a means whereby the intermittent siphon valve may be actuated by hand when and if necessary, to opened or closed position so that when opened, continuous drainage of the receptacle may be effected so as to completely empty the same.

The invention will be best understood from a consideration of the following detailed description taken in connection with the accompanying drawings, with the understanding that the invention is not confined to any strict conformity with the drawings but may be changed or modified so long as such changes or modifications mark no material departure from the salient features of the invention as expressed in the appended claims.

In the drawings:

Figure 1 is a view in front elevation of the lower front portion of a refrigerator with the lower part of the front door removed, showing the device of the present invention installed in the food chamber.

Figure 2 is a detail vertical section through 55

the central part of the rear portion of the refrigerator food chamber and through the water receptacle, the valve structure being in elevation.

Figure 3 is a view in elevation of the complete valve unit removed from the receptacle.

Figure 4 is a detail elevation of the valve plug removed from the encasing body.

Figure 5 is a vertical section through the valve plug on the line 5—5 of Figure 4.

Figure 6 is a vertical section through the valve body and the attached overflow tube.

Figure 7 is a view in top plan of the structure as illustrated in Figure 6.

Referring now more particularly to the drawings the present invention is illustrated in Figures 1 and 2, mounted in the bottom of a food chamber 10 of a conventionally illustrated refrigerator or ice box which is generally designated R, and the lower portion of which only is shown. In such refrigerators the drainage from the ice chamber above the food compartment is customarily carried off to the lower part of the food chamber through a tube 11 to be discharged into a suitable drainage or carry-off funnel, not shown.

In the present invention there is provided, in the place of the usual carry-off pipe or funnel which, customarily, extends through an opening 12 in the bottom or floor 13 of the refrigerator, an elongated open top receptacle 14 which rests upon the floor of the food chamber and extends the full width thereof, such receptacle having a bottom opening coinciding with the opening 12 in the food chamber 10.

The discharge of the drippings which are conveyed from the ice chamber through the tube 11 into the receptacle 14 is controlled by the novel intermittent siphon and continuous drain valve which is generally designated V. This valve fits into and forms a coupling between and closes the opening 12 and the opening in the bottom of the receptacle which is aligned therewith.

The valve comprises the short body 15 having adjacent the bottom end, the encircling flange 16 and below this flange the body is of the proper diameter to form a plug or fitting 17 which is tightly engaged in the opening 12, passing through the bottom opening of the receptacle.

Extending axially through the body 15 is a tapered seat 18 for the tapered rotary plug 19 and at the top edge of the body 15 is formed a recess 20 in which is located the rotary movement limiting pin 21 which is carried at the upper end of the plug 19. This pin limits the

movement of the plug valve 19 to two operating positions.

The numeral 22 designates oppositely disposed drain openings formed through the body 15 in close proximity to and above the flange 16 whereby water may be drained directly from the receptacle 14 through the plug as hereinafter described.

On an axis line extending perpendicular to the axis for the two openings 22, the body 15 has a lateral opening 23 in which is secured the angled lower end of the short stand pipe 24. The upper end of this stand pipe 24 is at a level, when the valve is fixed in the bottom of the receptacle, below the top of the receptacle so that when the water level rises in the receptacle, if it is not, for any reason, drained off through the hereinafter described siphon tube, it will flow off through this stand pipe. The stand pipe thus functions as an overflow preventing the level of the water rising beyond a pre-desired height.

Another function of the stand pipe is to permit air to flow upwardly into the upper part of the receptacle and into the food chamber and in addition allows for the escape of gases from within the food chamber.

The rotary plug 19 has a longitudinal passage therethrough, which passage is generally designated 25. At its upper end this passage is threaded to receive a coupling nipple 26 to which is threadably connected the end of the short leg 27 of a substantially J-shaped siphon tube which is generally designated 28. The longer leg 29 of the siphon tube carries a coupling 30 which, when the valve is set up, comes into close proximity with the bottom of the receptacle.

Joined to the siphon tube 28 in alignment with the short leg 27, is a handle stem 31 which is laterally turned at its upper end as shown.

The lower half of the valve plug passage 25 is of increased diameter as indicated at 25' and the lower part of the upper half of this passage is threaded for threaded connection with the upper end of an inside outlet or drain tube 32 which extends through the portion 25' of the plug passage and a substantial distance beyond the lower end of the plug.

The lower portion of the enlarged lower end 25' of the plug passage is also threaded for threaded connection with the upper end of the outside drain tube 33 through which the inside tube 32 extends, there being a very small space between the walls of the two tubes and the inside tube being of greater length and extending beyond the lower end of the outside tube as shown. These tubes extend down below the bottom 13 of the food chamber for discharge into any suitable receiver such as a pan 34 placed beneath the refrigerator or a carry-off or drain-pipe whichever may be found most desirable.

The plug 19 has the transverse aligned ports 35 which open into the enlarged upper portion 25' of the plug passage 25. Through these ports the water may be permitted to flow from the receptacle through the tube 33 and into the underlying drainage receiving pan.

In the operation of the present device the plug 19 may be turned, by means of the handle 31, either to a position where the ports 35 are in register with the openings 22 of the valve body so that the liquid can be drained directly from the receptacle or the plug may be turned to a position where one of the ports 35 registers with the opening 23 and therefore with the lower end of the stand pipe 24. If the valve is left

in this position it will be seen that as the water rises in the receptacle 14 it will also rise in the outside or long leg 29 of the siphon tube.

The height of the siphon tube is such that the top of the bend of the tube will be at substantially the maximum water level desired in the receptacle while the upper end of the stand pipe 24 is slightly above the upper end of the bend of the siphon tube. By this arrangement the siphon tube will always function to reduce the water level in the receptacle before such level reaches the top of the tube 24 unless the siphon tube should become closed or plugged for any reason, in which case the tube 24 will then act as an overflow to prevent the receptacle from running over.

By raising or lowering the nipple 30 which is upon free leg of the siphon tube the low water level in the receptacle can be regulated since, as is well understood in connection with the use of siphons, the water will continue to flow off from the receptacle through the siphon tube after siphonic action has started, until the level drops below the lower end of the leg 29. Therefore by raising or lower the nipple 30 the level to which the water in the receptacle is reduced by the action of the siphon, can be regulated within the limits of adjustment of the nipple on the siphon leg.

The action of the siphon is brought about by the use of a relatively small tube or a tube of small inside diameter so that by capillary attraction the water is caused to rise in tube 28 a little higher than the level of the water in the reservoir which causes the water to start flowing through the tube for discharge through the lower end of the conduit or out of tube 32. It will of course be understood that this action does not take place until the water level in the receptacle or reservoir 14 reaches the top of the bend in the tube 28.

I claim:

1. Automatic siphon draining means for a liquid receptacle having an outlet, a siphon tube having one end extending through said outlet and having its other end terminating within the receptacle adjacent to the bottom of the latter and a discharge conduit having one end at a predetermined elevation in the receptacle above the said other end of the siphon tube and having its other end opening downwardly around the first mentioned end of the siphon tube.

2. A siphon structure as set forth in claim 1, with means for establishing a fluid outlet connection between the lower part of the receptacle and said conduit adjacent the lower end thereof.

3. A self starting siphon comprising a siphonic tube consisting of a goose-neck connecting at one side with a long leg and connecting with a short leg at its other side, a short tube encircling and spaced from the longer leg adjacent the lower end thereof, and an upstanding tube connected at its lower end with the upper end of the short tube and forming a stand tube through which liquid may overflow to run down through the short tube and escape around the open end of the longer leg of the siphon tube.

4. A self starting siphon comprising a body having a passage therethrough, the passage being of enlarged diameter through a portion of its length to one end, a siphonic conduit having a part of said passage included therein, the conduit extending at one end beyond the said one end of said passage and beyond its other end, and a stand tube secured to the body and having its lower end opening into the portion of the passage

of increased diameter whereby liquid flowing down through the stand tube will pass downwardly from said passage around the extended end of the siphon conduit.

5. A valve structure comprising a body having a tapered plug valve seat bore therethrough, a port leading through the body into the bore, a tube extending coaxially with the bore and having one end secured to the body and opening therethrough into the bore, a rotary plug adapted to seat in said bore and having an axial passage therethrough, said passage being of increased diameter through a portion of its length to its lower end, a port opening through the body of the plug into the portion of the passage of increased diameter and adapted for selective registry with the first port and with the tube, and

means forming a siphon conduit having a long leg and a short leg, the long leg of the siphon conduit passing through the plug passage and beyond the lower end of the plug, the siphon conduit being spaced from the wall of the portion of the passage of increased diameter whereby fluid entering the said portion of the passage may flow downwardly around the adjacent end of the siphon conduit.

10 15 6. The valve structure as set forth in claim 5 with means carried by the siphon conduit forming a handle whereby said plug may be turned to selectively register the second mentioned port with the first port and with the lower end of the tube.

CHARLES H. WALBERT.
